COMBINED CORNER FIREPLACE AND HEATER

Bernard R. Rose, West Los Angeles, Calif., assignor to
Dyna Manufacturing Co., Los Angeles, Calif., a corpora-
tion of California

Filed Jan. 14, 1963, Ser. No. 73,175

Term of patent 14 years

(Cl. D81—7)

FIG. 1.

FIG. 2.

FIG. 3.

FIGURE 1 is a front elevation of my combined corner fireplace and heater;

FIGURE 2 is an elevation thereof rotated approximately 45° clockwise from the position shown in FIGURE 1;

FIGURE 3 is a top plan view of FIGURE 1.

The undisclosed sides and rear are substantially plain.
I claim:

The ornamental design for a combined corner fire-
place and heater, substantially as shown and described.
